Primary Examiner — Ricky Pham*(74) Attorney, Agent, or Firm* — Thompson Coburn LLP**(57) CLAIM**

The new, original, and ornamental design for a baking stand, as shown and described.

DESCRIPTION

FIG. 1 is a top view of a baking stand according to a first embodiment.

FIG. 2 is a bottom view thereof.

FIG. 3 is a side view thereof. The remaining side views are mirror images;

FIG. 4 is a perspective view thereof.

FIG. 5 is a top view of a baking stand according to a second embodiment.

FIG. 6 is a bottom view thereof.

FIG. 7 is a side view thereof.

FIG. 8 is a perspective view thereof.

FIG. 9 is a top view of a baking stand according to a third embodiment.

FIG. 10 is a bottom view thereof.

FIG. 11 is a side view thereof.

FIG. 12 is a perspective view thereof.

FIG. 13 is a top view of a baking stand according to a fourth embodiment.

FIG. 14 is a bottom view thereof.

FIG. 15 is a side view along a length thereof.

FIG. 16 is a perspective view thereof; and,

FIG. 17 is a side view along a width thereof.
